LIFE JACKET

Walter J. Vakousky, Seymour, and Stephen Comkowycz, Derby, Conn., assignors to The B. F. Goodrich Company, New York, N.Y., a corporation of New York

Filed Mar. 4, 1964, Ser. No. 78,861

Term of patent 14 years

(Cl. D71—1)

Fig. 1

FIG. 1 is a front elevation view of a life jacket embodying our new design; and

FIG. 2 is a side elevation view of the life jacket shown in FIG. 1.

The rear, not shown, is substantially flat and plain.

We claim:

The ornamental design for a life jacket, as shown and described.
